PERCY HAUSER AND ALBERT G. MC LAUGHLIN, OF ALTOONA, PENNSYLVANIA.

CANDLE-LAMP.

1,078,198.

Specification of Letters Patent. Patented Nov. 11, 1913.

Application filed September 18, 1912. Serial No. 720,946.

To all whom it may concern:

Be it known that we, PERCY HAUSER and ALBERT G. MC LAUGHLIN, both citizens of the United States, and residents of Altoona, in 5 the county of Blair and State of Pennsylvania, have invented a certain new and useful Improvement in Candle-Lamps, of which the following is a true and exact description, reference being had to the accompanying drawings, which form a part thereof.

Our present invention relates to candle lamps of the kind in which a candle is movably received in a candle tube and the latter 15 is provided with a stop at its upper end against which the upper end of the candle is pressed by resilient means located within the candle tube and acting against the lower end of the candle, the stop being formed 20 with an aperture of less diameter than the candle through which the wick of the candle projects, and above which combustion takes place.

The object of the present invention is to 25 provide an improved candle holder of the kind specified, which in addition to being comparatively simple in construction and reliable and efficient in normal operation, is adapted to effect a substantially complete 30 combustion of a candle used in it, and the avoidance of an objectionable accumulation of the melted candle body material in the candle tube proper or other portions of the lamp and to permit the ready removal of the 35 melted candle body material, which may accumulate in the lamp.

The various features of novelty which characterize our invention are pointed out with particularity in the claims annexed to 40 and forming a part of this specification. For a better understanding of the invention, however, and the advantages possessed by it, reference should be had to the accompanying drawings and descriptive matter 45 in which we have illustrated and described a preferred form of apparatus in which our invention may be embodied.

Of the drawings, Figure 1 is an elevation 50 of a candle lamp embodying our invention. Fig. 2 is a section on the line 2—2 of Fig. 1. Fig. 3 is a partial section taken similarly to Fig. 2, but on a larger scale than that figure, and Fig. 4 is a section of the candle tube on the line 4—4 of Fig. 2.

55 In the drawings, A, represents the candle

tube or tubular lamp body, which has an internal diameter appreciably greater than the diameter of the candles received therein. The tube A may be provided with the usual supporting bracket A' and is closed at its 60 lower end by the cap A² which may be brazed in place. To the upper end of the tube A there is removably secured an end member B. As shown, the end member B comprises a tubular body portion telescoping on the upper end of the member A and is provided at its lower end with a bead B'. The latter is notched, as indicated at B⁵⁰ in Fig. 4, to permit the locking projection A³ formed on the candle tube A to enter the 70 bead, whereby the end member B may be thereafter locked in place by giving it a slight rotative movement. The member B terminates at its upper end in a conical portion B² through which there is formed a 75 central aperture B³. In the construction illustrated, an annular candle stop member C preferably as shown in the form of a flat apertured disk of sheet metal is secured to the member B at the base of the conical portion B² as by spinning the member B to form a bead B⁴ surrounding the periphery of the member C. The member C is provided at its under side with a tubular candle 80 guide C² which may be soldered at its upper end to the disk C. The guide C² is of substantially the same diameter as, and snugly receives the upper end of the candle X mounted in the lamp. The central aperture C' of the body portion of the member C is of less diameter than the candle body 85 X and the portion of the member C projecting across the bore of the guide C² and forming in effect an inturned lip at the upper end of that guide, forms the portion 90 of the stop of the lamp against which the upper end of the candle directly bears. With the construction described, it will be observed that the member C and the conical portion B² of the member B unite to form 95 an annular trough B⁵ located above and surrounding the aperture C'.

The candle follower D which normally engages the bottom of the candle is cup-shaped and may be formed out of pressed brass, or the like, and is of a diameter at its upper edge, but slightly less than the internal diameter of the candle tube. Preferably as illustrated, the parts are so proportioned that the cavity in the upper side 100 105 110

of the follower D, while comparatively shallow, is deep enough to permit the upper edge of the follower to engage and make a tight joint with the lower side of the 5 candle stop disk C, as shown in Fig. 3, while at the same time an appreciable space is left between the bottom of the follower and the lower edge of the tubular candle guide C². The follower D is resiliently urged toward 10 the upper end of the candle tube by the spring E which extends between the follower and the bottom cap A². Advantageously the upper end of the spring E is soldered or otherwise attached to the follower D.

15 F, represents an annular member, secured to the candle tube adjacent its upper end and provided with draft apertures F' at its lower end, and serving to support the 20 lamp chimney G. H represents a soot collecting canopy extending over the top of the lamp chimney and supported from the bracket A' by the post H'.

25 To charge the lamp with a candle, the cap B is first removed and the candle is then inserted in the tube with its lower end received in and centered by the hollow follower D. After the candle is in place the cap B is again secured to the candle tube 30 with the upper end of the candle snugly received in the follower guide C² and the upper surface of the candle bearing against the candle stop C and with the candle wick projecting centrally through the aperture C'.

35 In operation with the candle wick ignited, the spring-pressed follower D constantly feeds the unconsumed portion of the candle body X upward thereby holding the solid portion of the candle against the stop, 40 until the shortening of the candle body permits the upper margin of the follower D to impinge against the underside of the candle stop disk C.

Prior to the engagement of the follower D 45 with the stop C, the snug engagement of the unmelted portion of the candle body with the stop C and guide C² prevents any appreciable amount of the melted candle material from passing below the stop and guide 50 and running down the side of the candle. Any small portion of the melted candle material which may pass below the guide C², is eventually received within the hollow follower D and has no opportunity to come in 55 contact with the interior wall of the candle tube. Any melted candle material which may rise above the candle stop C proper, collects in the trough B⁵, and is ultimately consumed. When the shortening of the 60 solid portion of the candle body permits the follower D to engage the stop C, the further combustion of the remaining candle material is not thereby prevented. On the contrary, unless the candle flame is purposely extinguished, combustion will ordi-

narily proceed until practically all of the candle material is consumed. As the combustion of the candle material proceeds after the follower D engages the stop C and the candle flame lowers relative to the candle stop, the consequent rise in temperature of the candle stop C, guide C², and eventually of the follower D, soon results in melting all of the remaining candle wax or tallow. At its maximum this melted candle material 70 is ordinarily sufficient in amount to fill the follower D to a level, indicated in Fig. 3 by the line X¹, which is appreciably above the lower end of the guide C². The clearance space provided between the lower 75 end of the stop C² and the bottom of the follower E permits the ready escape of melted candle material from the interior of the guide C² into the portion of the hollow follower D at the outer 80 side of the guide in the initial portion of this final stage of the candle consumption. This decreases the depth of the pool of the melted candle material contained within the follower and correspondingly decreases the 85 liability of the candle wick being submerged therein with a consequent premature extinction of the candle flame. As the combustion of the melted candle material thereafter continues, the ample clearance 90 space between the lower end of the guide C² and the follower permits the melted candle material to flow toward the bottom of the hollow follower, and in practice, under ordinary 95 conditions, almost all of the candle material will be consumed before the candle flame will be extinguished from natural causes; and there is practically no possibility of sufficient candle material being left 100 unconsumed to serve when cold as a cementing bond between the lower end of the guide C² and the follower D. 105

It is, of course, apparent that any candle material which may have collected in the trough B⁵ during earlier stages of the candle 110 operation will naturally drain out of this trough and be consumed in the final stage of operation.

Regardless of how soon the candle flame is extinguished after the stop C is engaged 115 by the follower D, it is obvious that the capacity of the cavity formed in the upper side of the latter is more than ample to hold the remaining candle material. Furthermore, the snug joint between the upper end 120 of the follower and the stop C will prevent any of the melted candle material from passing out of the follower and into contact with the walls of the candle tube proper under the jars or agitation to which the 125 candle lamp may be subjected in ordinary operation.

It is, of course readily apparent that any candle material remaining in the follower D after the candle flame is finally extin- 130

guished may be quickly and easily removed when the candle lamp is recharged. The avoidance of any accumulation of candle material within the candle tube sufficient 5 to interfere with the proper operation of the lamp, and the ease and rapidity with which the only portions of the candle lamp in which melted candle material may collect, may be cleaned, are characteristic features 10 of our lamp of great practical importance, as they save time and expense which have heretofore characterized the use of candle lamps, particularly in railway service wherein it has been commonly necessary to 15 subject the candle tubes to frequent cleaning out operations involving the use of steam as a cleaning and heating agent.

While in accordance with the provisions of the statutes we have illustrated and described 20 the best form of our invention now known to us, it will be apparent to those skilled in the art that changes may be made in the form of the apparatus disclosed without departing from the spirit of our invention, and that certain features of the invention 25 may sometimes be used with advantage without a corresponding use of other features.

Having now described our invention what

we claim as new and desire to secure by 30 Letters Patent is:

A candle lamp, comprising in combination a candle tube provided at its upper end with a stop for the upper end of an inserted candle, said stop being formed by a disk-like body extending across the tube and formed with a central aperture and being provided with a depending cylindrical guide surrounding said aperture and adapted to snugly receive the upper end of the inserted 40 candle, the internal diameter of said tube being greater, and the diameter of said aperture being less than the diameter of the inserted candle, and a spring pressed cup-shaped follower mounted in said candle tube, and adapted to surround said tubular guide and engage said disk when not held out of contact with the latter by an inserted candle, said guide and follower being so relatively proportioned that a clearance space exists between the lower end of said guide and said follower when the latter engages said disk.

PERCY HAUSER.

ALBERT G. McLAUGHLIN.
